US00D984425S

(12) United States Design Patent **(10) Patent No.:** **US D984,425 S**
Wright et al. **(45) Date of Patent:** **** Apr. 25, 2023**

(54) MOBILE PHONE PROTECTION CASE

(71) Applicant: **CATALYST LIFESTYLE LIMITED**,
North Point (HK)

(72) Inventors: **Joshua Wright**, Hong Kong (CN);
June Lai, Hong Kong (CN)

(73) Assignee: **CATALYST LIFESTYLE LIMITED**,
North Point (HK)

(**) Term: **15 Years**

(21) Appl. No.: **29/683,036**

(22) Filed: **Mar. 11, 2019**

(30) Foreign Application Priority Data

Sep. 11, 2018 (CN) 201830509876.8

(51) LOC (14) Cl. **14-03**

(52) U.S. Cl.

USPC **D14/250**

(57) CLAIM

The ornamental design for a mobile phone protection case, as shown and described.

DESCRIPTION

FIG. 1 is a perspective view including a front, bottom and one side of the mobile phone protection case;

FIG. 2 is a perspective view including a front, top and one side of the mobile phone protection case;

FIG. 3 is a perspective view including a front, top and opposite side of the mobile phone protection case;

FIG. 4 is a perspective view including a front, bottom and opposite side of the mobile phone protection case;

FIG. 5 is a perspective view including a rear, bottom and opposite side of the mobile phone protection case;

FIG. 6 is a perspective view including a rear, top and opposite side of the mobile phone protection case;

FIG. 7 is a perspective view including a rear, top and one side of the mobile phone protection case;

FIG. 8 is a perspective view including a rear, bottom and one side of the mobile phone protection case;

FIG. 9 is a front elevation view of the mobile phone protection case of FIG. 1;

FIG. 10 is a rear elevation view of the mobile phone protection case of FIG. 1;

FIG. 11 is an opposite side elevation view of the mobile phone protection case of FIG. 1;

FIG. 12 is a side elevation view of the mobile phone protection case of FIG. 1;

FIG. 13 is top plan view of the mobile phone protection case of FIG. 1; and,

FIG. 14 is a bottom plan view of the mobile phone protection case of FIG. 1.

1 Claim, 10 Drawing Sheets
